US0D1093285S

(12) **United States Design Patent** (10) Patent No.: **US D1,093,285 S**
(45) Date of Patent: ** Sep. 16, 2025

(54) **ENERGY STORAGE DEVICE**

(71) Applicants: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(72) Inventor: **Bo Jiang**, Beijing (CN)

(73) Assignees: **HICONICS ECO-ENERGY DRIVE TECHNOLOGY CO., LTD.**, Beijing (CN); **HICONICS ECO-ENERGY TECHNOLOGY CO., LTD.**, Beijing (CN)

(**) Term: **15 Years**

(21) Appl. No.: **35/521,005**

(22) Filed: **Apr. 25, 2024**

(80) **Hague Agreement Data**

Int. Filing Date: **Apr. 25, 2024**

Int. Reg. No.: **DM/237056**

Int. Reg. Date: **Apr. 25, 2024**

Int. Reg. Pub. Date: **May 24, 2024**

(30) **Foreign Application Priority Data**

Apr. 16, 2024 (CN) 202430213785.5

(57)

CLAIM

The ornamental design for energy storage device as shown and described.

DESCRIPTION

1. Energy storage device

1.1 : Perspective

1.2 : Perspective

1.3 : Front

1.4 : Back

1.5 : Left

1.6 : Right

1.7 : Top

1.8 : Bottom

(Continued)

FIG. 1.1 to FIG. 1.8 show an energy storage device according to the present design; the energy storage device is used for storing electric energy.

1 Claim, 8 Drawing Sheets
